UNITED STATES PATENT OFFICE.

CLAUDE CHAIZE AND ANTOINE CHAIZE, OF BELLEVUE-LA-DIGONNIÈRE, NEAR ST.-ETIENNE, FRANCE.

HEDDLE-MAKING MACHINE.

1,185,631.

Specification of Letters Patent.

Patented June 6, 1916.

Application filed February 24, 1913. Serial No. 750,430.

To all whom it may concern:

Be it known that we, CLAUDE CHAIZE and ANTOINE CHAIZE, citizens of the French Republic, residing at Bellevue-la-Digonnière, near St.-Etienne, in the Department of La Loire, France, have invented certain new and useful Improvements in Heddle-Making Machines, of which the following is a specification.

10 This invention relates to the manufacture of metallic heddles employed in looms and it has for its object to provide a semi-automatic machine which while being of very much simpler and stronger construction than the machines of the automatic type hitherto known for the manufacture of heddles allows of manufacturing the latter in such a manner that they can be used as they leave the machine, without requiring any further treatment by the operator attending the machine.

This machine forming the subject of the present invention is illustrated in the drawings accompanying the present specification, in which:

25 Figures 1 and 1^a show a front elevation of the machine, Figs. 2 and 2^a show a plan thereof, Fig. 3 is a detail view of a bell-crank lever mechanism for raising and lowering needles and other parts that serve for limiting the twists made in the heddles. Fig. 4 is a section on the line A—B of Fig. 1, and Fig. 5 is a detail view of a modified construction of one of the heads for forming the eyelets in the ends of the heddles. Fig. 35 6 shows the heddle made by this machine.

This machine consists essentially of a driving shaft 1 fixed in two supports or uprights 2 provided on the framing 3 of the apparatus and it receives its motion from a loose pulley 4 mounted on a fixed shaft 5. The hub of this pulley 4 is provided with a cam 6 fitting against a second cam 7 fixed on the end of the shaft 5. The arrangement is such that when the pulley rotates in the direction of the arrow (Fig. 1) the cams 6 and 7 are moved apart so as to produce a lateral movement of the pulley on the shaft 5 toward the interior of the machine in the manner of a claw clutch. When these two cams have moved beyond their projecting ends the cam on the hub of the pulley falls back into the notch formed behind the fixed cam in consequence of the pressure exerted upon the said hub by a spring 8 provided on the shaft 5 between the pulley and the framing of the apparatus. This approach

of the cams 6 and 7 to each other thus returns the pulley into its initial position on the right hand. This pulley 4 is provided with teeth on a part of the inner surface of its rim and when it has terminated its movement toward the left, it engages by means of this toothed portion 9 with a pinion 10 fixed on the driving shaft 1 in such a manner as to impart intermittent rotary motion to this shaft.

On a slotted bench 11 formed as a slide-way, there are bolted two puppet bearings 12, 13 carrying spindles 14, 15 for producing the desired twists in the heddles that are being manufactured. These spindles are provided with heads 16, 17 for forming the end eyelets and they are rotated by the driving shaft 1 through the medium of toothed wheels 18 mounted on this shaft, and of toothed pinion gearing 19, 20 arranged in a similar manner in both puppets. The head 16 comprises a matrix 21 of the shape which it is desired to give to the end eyelets and capable of being embedded into the said head in such a manner as to fit in the recess 22. By means of a small rod 23 fixed on this matrix, sliding in the lower part of the head 16 and provided with a spring 24 arranged between the projection 25 of the head and the body of the matrix 21, the latter is returned into its normal position (Fig. 1). This matrix 21 has a small vertical slit 26 of sufficient width to receive the end of the metal wire employed in the manufacture of the heddles. This small vertical slit is arranged preferably diagonally in the body of the matrix 21 and ends in a small horizontal notch 27 so that when the matrix is inserted into the head 16, the metal wire introduced into the slit and engaged in this notch 27 will be cut by shearing. The slit 26 in the matrix 21 may also be parallel to the major axis of this matrix as indicated in Fig. 5. In this case, the end of the wire will be passed around a small rod 21' adapted to slide in an extension of the head 16 and be held on the latter by a small spring. This rod is raised slightly for the purpose of passing the end of the metal wire below its head 21'.

For the purpose of cutting the end of the wire, the matrix 21 is normally inserted by hand and returned into its initial position by a spring 24. In the case of metal wires of considerable thickness this matrix may however be inserted if necessary by means

of a lever arranged in a suitable manner below an extension of the head 16, and having its shorter arm connected to the lower end of the matrix die. The head 17 of the other 5 spindle 15 is likewise provided with a matrix die 28 having the same shape as the die 21. This die 28 is also capable of being lowered in order to occupy the recess 29 provided for this purpose and it is returned 10 into its initial position by a spring 30 mounted on the small sliding rod 31 of the die between the body of the latter and the short arm 32. At the outer end of the two spindles 14, 15 there is mounted on an extension 15 of these latter, a stop 33 provided with a set screw 34. A coiled spring 35 is arranged on each of these outer extensions of the spindles between the stops 33 and the body of each puppet. These springs 35 exert 20 a certain pressure against the body of the puppet through the medium of a washer 36 and a set of balls maintained in place by a ring 37. Each spindle is thus able to yield to a certain extent to a pull exerted 25 upon it toward the center of the bench 11, but it is prevented from moving back beyond a certain limit by the action of a shoulder 38 formed on the forward part of each spindle which carries the head for making 30 the eyelets.

The two puppets 12, 13 with their spindles and heads for making the end eyelets are fixed on the bench 11 by means of tightening screws 39 in such a manner that they 35 can be shifted in accordance with the length which the heddles are to have. The toothed wheels 18 can therefore be shifted and they are likewise provided for this purpose with tightening screws in their hubs. 40 On the bench 11 there is also arranged between the two puppets a support 40 constituting a bearing which maintains a toothed pinion 42 between its uprights 41. This pinion 42 is cut away at a portion of 45 its circumference in such a manner as to form a gap 43 (Fig. 2) corresponding to a similar gap 44 provided in the tops of the two uprights 41. The said pinion 42 moreover contains in the bottom of the gap 43 a tongue or matrix die 45 serving for the formation of the eye of the heddle, the shape 50 of this eye being determined by the shape of the said tongue. The pinion 42 is rotated by the toothed wheel 46 mounted on the 55 driving shaft 1. The support 40 for the toothed pinion 42, as also the puppets at the ends of the bench, are fastened to the said bench by a screw provided with a nut.

On each side of the pinion 42 there is arranged 60 a blade or part 47 mounted on a vertical rod 48 adapted to be raised and lowered in the socket 49 provided with a vertical slit 50 wherein the part 47 can be engaged in its downward movement. Each 65 socket 49 has a small base plate and a fixing

screw provided with a nut 51 whereby the sockets can be fixed on the bench 11 and can be shifted when necessary. The small rods 48 that carry the parts 47 are connected by links 52 to a horizontal bar 53 arranged below the bench 11. Near the puppet 13 there is provided on the bench 11 a socket 54 which is likewise fixed to the bench by means of a screw and a nut. This socket 54 is traversed by a small rod 55 which carries at its upper end a tongue 56 and is connected at its lower end by a ring 57 to the bar 53. Another socket 58 is arranged on the said bench 11 near the puppet 12. This socket is also fixed to the bench by means of a screw and nut. Inside the socket 58 there is arranged a small rod 59 carrying at its upper end tongs 60 consisting of two small jaws one of which is preferably slightly shorter than the other in order to facilitate the introduction thereinto of the end of the wire used in the manufacture of the heddle. The shorter jaw of the tongs is formed inside with a horizontal notch by which the end of the wire held in the hand 90 is sheared when the tongs 60 move down into the interior of the socket 58. For the purpose of avoiding a faulty shearing of the wire through "play" in the tongs 60, the tongs are surrounded with a split sleeve 60' 95 upon which acts a set-screw 60".

The lower end of the rod 59 provided with the said tongs is connected by a ring 61 to the horizontal bar 53. The tongs 60 as also the tongue 56 and the two parts 47 can be 10 raised and lowered by means of the bar 53. This bar 53 is connected to two bell-crank levers 62 which are capable of rocking in vertical planes on the axis 63 upon the horizontal cross bars 64 of the framing 3 of the 10 apparatus (Figs. 2 and 3). A second bar or rod 65 is arranged moreover on the frame 3 and is held in the bearings 66. This bar 65 is provided at one end with a bell-crank lever 67 carrying a roller 68 at its end, and at its other end with two small cranks 69 which connect said bar to two small connecting rods 70 which are adapted to be moved forward and backward in guiding sleeves 71. When the lever 67 is lowered the connecting 11 rods 70 are moved forward toward the bell-crank levers 62 and by engaging in a notch 72 provided on the angle of each bell-crank lever the latter levers are caused to oscillate downward thereby producing a descending 12 movement of the bar 53 and the parts connected therewith. The small tongs 60, the parts 47 and the tongue 56 are moved down by this downward movement and caused to enter into their sockets. On raising the lever 12 67 and thus withdrawing the connecting rods 70 from the notches 72, the bar 53 is raised again by the spring 73 that connect the lower arms of the levers 62 to the bearings 74. On thus rising again, the bar 53, 13

the tongs 60, the parts 47 and the tongue 56 move above their guide sockets into their initial positions (Fig. 1). Coil springs 75 which are fixed at one end to the sleeves 71 and 5 at their other end to a ring provided on each connecting rod 70 facilitate the advance of the latter rods toward the bell-crank levers 62.

In the operation of the machine the lowering 10 of the bar 53 and of the parts 60, 47 and 56 fixed upon the latter, is produced by means of cams 76 mounted on the driving shaft 1 and provided with a projection 77 which is adapted to strike rollers 78 mounted 15 on the ends of the upper arms of the levers 62. These levers are thereby caused to rock downward and thus move the bar 53 in the said direction. The rise of this bar 53 is produced by means of a projection 79 20 which is provided on the pulley 4 and which strikes at a suitable moment against the roller 68 provided on the end of the lever 67.

On the end of the driving shaft 1 opposite to the end where the driving pulley engages, 25 there is keyed a cam 80 having a lateral projection 81 (Fig. 1) ending in a second cam 82.

On the lateral projection 81 of the cam 80 there is mounted loose another cam 83 which 30 is maintained in its position of rest by a pawl 84 having the form of a bell-crank lever (Fig. 4) adapted to pivot on an axis 85 on the framing of the apparatus and kept in engagement in a notch 86 of the cam 83 by means of a coil spring 87. A counter pawl 88 provided on the cam 80 allows of disengaging the retaining pawl 84 from its notch and thus liberating the cam 83 when the fixed cam 80 is rotated in the opposite direction 35 to that of the hands of a watch.

The loose cam 83 has a slot 89 provided with a tightening nut 90 which can be shifted if necessary. A notch provided in the fixed cam 80 allows of shifting the nut 90 and 40 forms an abutment 91 against which the nut 90 is made to strike at a given moment. A fourth cam 93 is mounted loose on the end of the driving shaft 1 and is connected by a chain provided with a coiled spring 94 to the framing of the apparatus. This fourth cam 93 has a pawl 95 bearing against the cam 82 and adapted to engage at the proper moment in a notch 96 formed in the cam 82.

On rotating the driving shaft in the opposite direction to that of the hands of a watch the retaining pawl 84 is first disengaged from the loose cam 83. The fixed cam 80 continues to rotate and then carries with it the cam 83 in consequence of the nut 90 being made to bear against the stop notch 91. The cam 82 continues to rotate since it is formed in one piece with the fixed cam 80, and this cam 82 in encountering with its notch 96 at a given moment the pawl 95 provided on the fourth

cam 93, carries the latter around with it and thus produces a strong tension of the spring 94. This rotation of the cams 80, 82, 83, and 93 is continued until the retaining pawl 84 engages again in the notch 70 of the cam 83 and thus arrests the latter. This moment corresponds to the unclutching of the driving pulley. The rotation of the cams which has caused the tensioning of the spring 94 is thus stopped, and the 75 cam 93 which is always in engagement with the cam 82 and consequently also with the cam 80 is returned to the rear by the action of the spring 94. Since the cams 80 and 82 are fixed on the driving shaft they impart to the latter and its gear wheels a return motion which is arrested by a tappet 97 fixed on the fixed cam 80 when it arrives at the end of the slot 89 of the loose cam 83 that is held at that moment by the 85 pawl 84. The rotation of these cams and the driving shaft in the reverse direction will be so much the longer as the driving of the loose cam 83 shall have been retarded and the nut 90 shall have been placed farther in the slot 89 with reference to the stop 91 of the cam 80. At this moment, the parts are in the position they occupied at the beginning and they are ready for a fresh operation. The driving pulley 4 will have 90 continued to rotate in the meantime and will again come into engagement with the pinion 10 on the driving shaft in such a manner as to produce a fresh forward rotation of the latter which is followed by a 95 rotation in the reverse direction and so on as hereinbefore described. If necessary when for any reason the operator desires to retard the restarting of the machine the pulley 4 can be maintained as desired 100 in the declutched position by means of an auxiliary de-clutching device preferably at the foot of the machine. At the end of each rotation in the reverse direction the pawl 95 of the cam 93 is disengaged from the cam 105 82 by means of a lever 92 which is mounted on the rear bar 65 and is actuated at the same time as the lever 67 by means of the projection 79 provided on the driving pulley.

The operation of the entire apparatus and the formation of the metal heddles are as follows: The steel or iron wire employed in the manufacture of the heddles after having been cut to the desired length, is inserted 110 with one end into the small slot 26 in the die 21 in the head 16 and is brought behind the tongs 60, the parts 47, the tongue 56, around the second die 28 in the head 17, in front of the parts 56, 47, 60, and back 115 120 around the die 21, being finally inserted with its other end into the tongs 60 and held therein by pulling the said end slightly by hand. The driving pulley 4 is then 125 caused to engage by reason of the moving 130

apart of its cams and thus produces by means of the toothed wheels 18, 46 and the pinions 19, 20, rotation of the spindles 14, 15 with their heads 16, 17 for forming the 5 end eyelets on the one hand, and rotation of the central pinion 42 on the other hand. By this means a first twist is imparted to the double wire stretched between the two heads 16, 17. In this first twisting, the eye 10 is formed by the rotation of the tongue or die 45 in the central pinion 42, the twisting necessary for the formation of this eye being determined by the two parts 47 which are engaged between the two lengths of 15 wire. On the other hand the two end eyelets are formed in this first twisting operation and the latter is limited for this purpose on the side of the head 17 by the tongue 56 and on the side of the head 16 by the 20 tongs 60, these two parts 56 and 60 being likewise engaged for this purpose between the two lengths of wire. This first twisting with formation of the eye and the two end eyelets is terminated at the moment when 25 the stops 77 of the cam 76 provided on the driving shaft 1 strike the rollers 78 of the bell-crank levers 62 and by rocking the latter cause a downward movement of the bar 53. This bar 53 carries down with it the 30 tongue 56, the parts 47 and the tongs 60 and causes them to enter into their guiding sleeves. The tongs 60 in descending into its socket 58 cut off, flush with the heddle that is being formed, the end of the steel 35 wire which is held in the hand.

The first stage of the operation being ended it is now necessary to twist the two lengths of wire of the leach throughout the extent comprised between the eye and the 40 two end eyelets. The spindles 14, 15 and consequently the heads 16, 17 which hold the end eyelets of the heddle, thus continue to turn and thereby produce in the two halves of the heddle the desired twist until the 45 driving pulley disengages with its toothed sector from the pinion 10 of the driving shaft 1 and is pushed back into its initial position by the spring 8. As soon as this pulley has become disconnected the herein- 50 before described rearward movement or reverse rotation takes place which is produced by the spring 94. The heddle is thus subjected also to a rotation in the reverse direction so as to produce what is known as 55 the alinement of the heddle, that is to say for bringing the two end eyelets of the heddle in one and the same plane while the eye remains in a different plane, which may be at right angles or not at right angles 60 to the first plane. This operation ends the second stage of the manufacture of the heddle and there now remains only to drive in the two dies 21, 28, the former of which cuts by shearing the other end of the wire 65 of the heddle which is situated inside the

loop in the slit 26 of the die 21. The leach is now completely finished and leaves the apparatus ready for insertion in the heddles or bars of the heddle frames without requiring any further treatment by hand. 70

Two supports consisting of flat rods having the shape of the end eyelets of the heddles can be fixed in an adjustable manner at the front of the framing of the apparatus and may serve for threading the heddles 75 thereon as they leave the apparatus. While the heddle is being removed from the apparatus the driving pulley in continuing its rotation impinges with its projection 79 against the roller 68 of the lever 67 and in this manner returns by means of the hereinbefore described arrangement of bars and bell-crank levers, the tongs 60, the parts 47 and the tongue 56 to their operative positions (Fig. 1). 80

The apparatus is now ready to form another heddle. The devices which serve for the formation of the eye and the end eyelets of the heddle may naturally vary as regards their dimensions and their shapes and it is to be understood that any other suitable modifications may be made in the construction of the hereinbefore described and illustrated apparatus without departing from the nature of the present invention. 85

Having now particularly described and ascertained the nature of our invention and in what manner the same is to be performed, we declare that what we claim is:

1. In a machine for making twisted metal 100 heddles, a drive shaft, revolvably mounted dies and an intermediate die connected for rotation with said shaft, means co-operating with said dies upon rotation of the same to twist a loop of wire adjacent said dies to form the end eyelets and the eye in the metal heddle, mechanism for rotating said drive shaft, automatically actuated means for disengaging said mechanism from said drive shaft after a predetermined rotation of the latter, means including an energy storing device and a plurality of cams for storing energy in said device during the rotation of said shaft to form the eyelets in the metal heddle, said energy storing device rotating 105 said drive shaft through said cams in the other direction upon disengagement of said mechanism from said drive shaft. 110

2. In a machine for making twisted metal 115 heddles, a drive shaft, revolvably mounted end dies and an intermediate die, gearing for driving said dies from said shaft, means for driving said shaft, automatic means for disengaging said driving means from said shaft after a predetermined rotation of the same, and means including a tension device and a plurality of cams for reversing the rotation of said driving shaft after it has been 120 disengaged from said driving means. 125

3. A machine for making twisted metal 130

5 heddles from a length of wire, comprising two dies of a shape to form the end eyelets of the heddle, an intermediate die of a shape to form the eye in the heddle, means for securing the ends of a wire adjacent one of said end dies, said wire being arranged in a loop around the said end dies with the intermediate die between the sides of the loop, means for rotating said dies, means coöperating with said dies when rotating to tightly twist the wire adjacent said dies to form the end eyelets and eye in the heddle, means for withdrawing said coöperating means after an initial rotation of said dies whereby upon further rotation of said dies the loop of wire is twisted intermediate the eyelets and eye, and means for cutting the ends of the wire adjacent that one of the end dies at which the ends of the wire are secured.

10 4. A machine for making twisted metal heddles from a length of wire, comprising two dies of a shape to form the end eyelets in the heddle, an intermediate die of a shape to form the eye in the heddle, means for securing the ends of a wire adjacent one of said end dies, said wire being arranged in a loop around the said end dies with the intermediate die between the sides of the loop, means for rotating said dies, means coöperating with said dies when rotating to tightly twist the wire adjacent said dies to form the end eyelets and eye in the heddle, means for withdrawing said coöperating means after an initial rotation of said dies whereby upon further rotation of said dies the loop of wire is twisted intermediate the eyelets and eye, and means for reversing the rotation of said dies and for bringing the end eyelets into the same plane.

15 5. A machine for making twisted metal heddles from a length of wire, comprising two end dies of a shape to form end eyelets in the heddle, an intermediate die of a shape to form the eye in the heddle, means for securing the ends of a wire adjacent one of said end dies, said wire being arranged in a loop around the said end dies with the intermediate die between the sides of the loop, means for rotating said dies, means coöperating with said dies when rotating to tightly twist the wire adjacent said die to form the end eyelets and eye in the heddle, means for withdrawing said coöperating means after an initial rotation of said dies whereby upon further rotation of said dies the loop of wire is twisted intermediate the eyelets and eye, and means for reversing the rotation of said dies to bring the end eyelets into the same plane, and for positioning the eye of the heddle in a plane at an angle to the plane of the end eyelets.

6. In a machine for making twisted metal heddles from a length of wire, a die around which the length of wire is adapted to be disposed in the loop, means for securing one end of the loop in the die, means adjacent said die for securing the other end of said loop, and means for rotating said die to twist a loop of wire intermediate said securing means and die to form an end eyelet in the heddle.

7. In a machine for making twisted metal heddles, a rotatable end die of a shape to form the end eyelet in the heddle and around which die a length of wire is adapted to be disposed in a loop, means for securing one end of the loop in said die, means for securing the other end of said loop adjacent said die, means for rotating said die, said securing means coöperating with said die to twist the loop intermediate said securing means and the die to form the end eyelet in the heddle, said securing means comprising a cutting member for severing the wire close to the twisted portion after the formation of the eyelet in the heddle.

8. In a machine for making twisted metal heddles, two revolubly mounted dies of a shape to form the end eyelets in the heddle, an intermediate revolubly mounted die arranged in the plane of said end dies, movably mounted members adjacent each of said end dies and on each side of said intermediate die, and means for projecting said members into the plane of said dies and thereafter withdrawing them from said plane, one of said members comprising a pair of tongs adapted to hold one end of the wire when said tongs are projected into the plane of said dies, said tongs having at least one cutting edge to sever the wire upon the withdrawal of said tongs from the planes of said dies.

9. In a machine for making twisted metal heddles from a length of wire, comprising two revolubly mounted dies of a shape to form the end eyelets in the heddle, an intermediate die of a shape to form the eye in the heddle, means for securing a length of wire around said end dies in the form of a loop with the intermediate die between the sides of the loop, movably mounted members positioned adjacent each end die and on each side of said intermediate die having their ends normally projecting between the sides of the loop of wire, and gearing for rotating said dies to twist the wire intermediate said members and dies and to thus form the end eyelets and eye in the wire.

In testimony whereof we affix our signatures.

CLAUDE CHAIZE.
ANTOINE CHAIZE.
